CLAIM

The ornamental design for a toy vehicle with removable handle, as shown and described.

DESCRIPTION

FIG. 1 is a front, top and right side perspective view of a toy vehicle with removable handle showing our new design;

FIG. 2 is a rear, bottom and left side perspective view; FIG. 3 is a front, top and right side perspective view thereof with the handle member shown in an exploded condition;

FIG. 4 is a top plan view with the handle in place; and FIG. 5 is a bottom plan view thereof.
